 6 Claims. (Cl. 230—56)

The present invention relates to a new free piston machine, intended more particularly to be used for compressing air to be employed for supplying various receiving mechanisms.

The invention applies, nevertheless, to devices for compressing other gases, and is also applicable to devices such as gas generators or gasifiers, that is to say, devices in which the energy produced by the motor element serves to compress and to feed a mass of air at a pressure which can be varied, the mass of air being utilized at least partly for the scavenging and the feeding of said motor element, said energy being finally collected in the form of heat and pressure in the exhaust gases which are utilized in a machine such as a turbine.

It is an object of the present invention to create a new machine which is simple of structure and effective in operation and as compact as possible.

It is another object of the invention to provide a machine wherein the number of movable parts is reduced with respect to the number of movable parts of similar machines.

It is a particular specific object of the invention to eliminate synchronizing mechanisms for the regulation of movable parts, which synchronizing mechanisms are provided in the known art.

It is another further object of the invention to provide a machine of the type specified which is easily cooled only by circulation of air, such air being caused to rapidly circulate onto the more heated parts of the machine without the aid of any blower or similar device.

According to the invention, the power-driven compressor comprises a hollow body divided into two variable volume compartments by a diaphragm associated on one slide with at least one motor piston movable in a motor cylinder of the two-stroke Diesel cycle type, said diaphragm being subjected on its other side to a damping caused by the compression work of a charge of a gas to be compressed and to a resilient stress developed by a charge of gas, the compression of which causes the return stroke of said diaphragm and motor piston.

The diaphragm advantageously is formed by a piston placed inside a cylinder this piston confining inside said cylinder two variable volume chambers in which air is successively sucked in and compressed, one of said chambers communicating with a collector for exhaust compressed air leading to an utilization device, and the other chamber communicating by an intermediate housing with scavenging ports of the Diesel two-stroke cylinder into which slides said motor piston which is rigidly connected to said piston forming the diaphragm.

Various other characteristics of the invention will moreover be revealed by the detailed description and claims which follow.

Forms of embodiment of the invention are shown, by way of non-restricting examples, in the attached drawings 65 in which:

2

FIGURE 1 is a longitudinal cross elevation showing one form of embodiment of the power-driven compressor according to the invention.

FIGURE 2 is a section at a smaller scale seen substantially along the line II—II of FIGURE 1.

FIGURE 3 is a section at a smaller scale taken substantially along the line III—III of FIGURE 1.

FIGURE 4 is a partial diagrammatical section seen substantially along the line IV—IV of FIGURE 1.

FIGURES 5 and 6 are diagrammatical elevation-sections, showing two alternative embodiments of the device.

As shown by the drawing, and more particularly, FIGURE 1, the free piston machine device comprises a main casing 1, hereafter called "compression casing," which internally delimits a cylinder 2, said compressor casing further being provided on its periphery with cooling fins 3. At one of its ends, that shown to the right of FIGURE 1, the casing 1 supports a sheath 4 confining a cylinder 5 and a collector 6 communicating with the interior of the cylinder 2 by at least one outlet flap-valve 7. The cylinder 5, formed by the sheath 4, is closed at its end by a part 8 and also confined by a collar 9 intended to contain a mechanism 10 whose function is explained in the following description. As shown by the drawings, the sheath assembly 4 extends from a projecting annular rim 11 which is provided at the end of said cylinder 2.

A projecting annular border 12, whose peripheric rim confines a strap or flange, preferably extends obliquely 30 in relation to the axis of the cylinder 2 and projects to a greater extent than that of the fins 3 with which this cylinder is provided. The middle part of the border 12 acts for supporting inlet flap-valves 13. Other inlet flap-valves 14 are also provided in the casing 1 near to the 35 annular rim 11, which is used, as well as the annular border 12, for maintaining a cylindrical part 15 comprising, at its middle part, a porous element 16, so that said part 15 thus forms a filtering cartridge confining, with the periphery of the casing 1, a chamber 17 acting for channelling the air intended to pass during the working of the 40 device, in directions whereby this air raises the inlet flap-valves 13 or 14 respectively.

The peripheric strap or flange formed by the projecting border 12 is used for screwing a second casing 18, hereafter called "driving casing." The side of the driving casing turned towards the compressing casing is closed by a partition 19 in which openings 20 (FIG. 2) are provided for positioning flap-valves 21 intended to enable a chamber 22 to communicate, confined between the compression and driving casings 1 and 18, with a collector 23 provided in said casing 18.

In addition to the openings 20, the partition 19 confines the mouthportion of two cylinders 24 and 25. The cylinders 24 and 25, as well as the other parts, both for the driving casing 18 as well as the compression casing 1, are advantageously made of light metal alloys. Inside said cylinders, a lining is provided that may be made of a hard metal, for example, of hard chromium, or of a cast-iron addition, or else, as shown in the drawing, by the 60 insertion of thin linings 26.

The two cylinders 24 and 25 are provided on their periphery and over most of their length, with cooling fins 27. Moreover, the front part of the two said cylinders communicates, by a large dimensioned duct 28, called "transfer." Furthermore, the cylinder 25 also communicates with the collector 23 through ports 29 advanta-

geously provided over its entire periphery, as can be seen, in particular, in FIGURE 2. The ports 29, as well as the transfer duct 28, act for the circulation of the scavenging air of the cylinders, as will be explained farther on.

30 denotes an exhaust manifold provided in the driving casing, this exhaust manifold communicating with the interior of the cylinder 24, by ports 31. The terminal part of the cylinders 24, 25, i.e., that showing at the left part of FIGURE 1, is closed by means of a finned cylinder head 32 in which, as shown in particular in FIGURE 4, ducts 33, 34 are provided, communicating with each other and with a channel 35 in which a pump-injector 36 of a known type is fixed, whose working is subjected to the pressure prevailing in the driving cylinders, the delivery variation being regulated, for example as known per se, by a pneumatic regulator sensitive to the delivery pressure of the machine. This regulator being well known in itself and consequently it is no more described since it does not constitute structurally a part of the invention. This injector can also be controlled by electrically operated mechanism estimating the position of the mobile unit which is described hereafter.

The various cylinders described above, which confine both the compression casing 1 as well as the driving casing 18, act as a housing for a single mobile unit, which, in the example shown, comprises a compressor piston 37 between the chamber 22 and the interior of the cylinder 2, this compressor piston supporting, on the one hand, a piston 38 engaged in the cylinder 5, confined by the sheath 4, and one the other hand, two driving pistons 39 and 40 placed in the cylinders 24 and 25, as shown in particular in FIGURE 1.

It is advantageous that the combustion chambers which are confined inside the cylinders 24, 25 between the pistons 39, 40 and the cylinder head 32 and which are denoted by the reference numerals 41 and 42, have a "wedge" shape in order to ensure satisfactory combustion of the fuel mixture. In this case, the piston heads 39, 40 are so shaped as to correspond to that of the internal walls of the cylinder head, or else, as shown said piston heads 39, 40 are provided with extended caps 43.

The position of the mobile unit comprising the various pistons described above, and which is shown in FIGURE 1, corresponds to that for which the fuel mixture contained in the combustion chambers 41 and 42 begins to ignite. The combustion of this mixture has the effect of thrusting this mobile unit towards the right, i.e., in the direction of the arrow f_1 , and hence the air in the cylinder 2 is progressively compressed and delivered through the outlet flap-valve 7 into the collector 6, connected to a tank (not shown).

During this movement, the compressor piston 37 sets up a depression in the chamber 22 whose volume is progressively increasing, and consequently, air is sucked through the filtering cartridge 15, then this air, after having flowed over the fins 3 with which the compression casing 1 is provided, penetrates into said chamber 22 obviously raising the inlet flap-valve or flap-valves 13.

The stroke in the direction of the arrow f_1 of the mobile unit has the effect, moreover, of compressing the gas charge contained in the cylinder 5. The latter being closed, a power is thus stored up which is then utilized, at the end of the driving stroke, for returning the mobile unit to the position shown in the drawing.

During the return stroke described above, i.e., during that corresponding to the setting free of the power stored up in the cylinder 5, the compressor piston 37 causes a depression in the cylinder 2, and consequently, air is sucked through the filtering cartridge 15 and through the chamber 17 while passing through the inlet flap-valves 14. As in the preceding case, this air flows over the fins of the compression cylinder, which ensure an efficient cooling of the latter.

5 This return stroke in the opposite direction to that of the arrow f_1 , thus causes the compression of the air previously admitted into the chamber 22; this air is thus progressively delivered through the flap-valves 21 into the scavenging manifold 23 where it is compressed, seeing that at this moment, the piston 40 closes the ports 29.

10 As can be clearly seen from the drawing, at the end of the driving stroke, i.e., the one in the direction of the arrow f_1 the piston 39 progressively exposes the exhaust ports 31, so that the burnt gases in the cylinder 24 can thus escape towards the manifold 30. This also applies to the burnt gases in the cylinder 25, seeing that the transfer duct 28 is exposed, and that hence a communication exists between the two said cylinders. At the moment when the piston 40 begins to expose the scavenging ports 29, the air compressed during the preceding return stroke of the mobile unit in the collector 23, is thus brought to pass firstly into the cylinder 25, then through the transfer duct 28 provided near to the cylinder head 32, in the cylinder 24, this compressed air discharging the burnt gases while assuring the filling of the two said cylinders, and then once more to be compressed at the moment of the following return stroke of the mobile unit, at the end of which the fuel is injected by the pump-injector 36.

15 As explained in the foregoing, the device is provided with a housing 9 enclosing a mechanism 10. The housing 9 delimits a recess, intended to contain a charge of air, for example compressed by means of a hand pump, and the mechanism 10 comprises a hand-controlled valve which is not shown and which is intended to allow the putting into communication of the recess of the housing 9—when wishing to start up the machine—with the interior of the cylinder 5, into which a charge of compressed air is thus injected, which has the effect of rapidly thrusting the mobile unit in the opposite direction to that of the arrow f_1 , to cause the compression of the air contained in the combustion chambers 41, 42, and consequently, to start off the first driving stroke of the machine.

20 FIGURE 5 shows a first alternative revealing constructive simplifications, enabling the carrying out of devices intended for special purposes. According to this alternative, the mobile unit comprises only one compressor piston 37 and a single driving piston 39a, extending coaxially with said compressor piston 37. According to this alternative, the cylinder 5, intended to store up the return power, is also suppressed, but in this case, the exhaust flap-valve 7, provided in the cylinder 2 is placed at a certain distance from the end of the latter, in order to increase the detrimental volume, and consequently, thus create a closed enclosure intended to store up the return power of the mobile unit.

25 As in the example described above, with reference to FIGURES 1 to 4, the air sucked in and then compressed is discharged from the chamber 22 and directed by the manifold 23 into the driving cylinder controlling the driving piston 43, this driving cylinder obviously having the same exhaust ports 31 which communicate with the manifold 30 acting for the evacuation of the burnt gases. The power-driven compressor device described above, with reference to FIGURE 5, is particularly simple to produce, and although in actual practice its output is slightly less than that of the device previously described, this conception enables low powered machines to be made in a very economical manner thus advantageous for numerous purposes.

30 When it is desirable that the overall dimensions of the power-driven compressor should be as small as possible and this, while retaining all the advantages afforded by the device described with reference to FIGURES 1 to 4, more particularly with regard to the advantages obtained by the arrangement with two driving cylinders, it is possible to form the volume storing up the return power as

described in FIGURE 5, i.e., by increasing the detrimental space at the bottom of the compression cylinder 2 which can be obtained by placing the outlet flap-valve 7 laterally at a certain distance from the bottom. It is also possible to construct the power-driven compressor as shown diagrammatically in FIGURE 6, in which the various main components shown are denoted by the same reference numerals as in FIGURES 1 to 4. More particularly, for reducing the length of the power-driven compressor, the sheath 4, confining the cylinder 5 storing up the return power, is suppressed, and in this case, the compression casing 2 is closed by a bottom 44 extending level with the annular border 11; this bottom supports two fixed pistons 45 and 46 which penetrate into cavities 47 and 48 made inside the compressor piston 37 and of each of the two driving pistons 39 and 40, said cavities 47 and 48 obviously having variable volumes during the movement of the mobile unit, and consequently these variable volumes, previously filled with a charge of air, act as an accumulating container for the return power to be developed, in order to produce this displacement of said mobile unit in the direction for which this combustion air must be compressed in the cylinders 24 and 25. Although not shown, the arrangement according to FIGURE 6 can also be put into operation in the power-driven compressor as described with reference to FIGURE 5, in a power-driven compressor comprising only one driving piston and a single compressor piston.

It will be obvious to those skilled in the art that various changes may be made without departing from the spirit of the invention and therefore the invention is not limited to what is described in the specification, but only as indicated in the appended claims.

We claim:

1. A free piston machine comprising a motor casing and a compression casing in aligned relationship, a single movable unit located in said motor and compression casing to be reciprocated therein, said movable unit comprising a first piston located in said compressor casing and delimiting therein an inlet scavenging air chamber and a compression chamber for the compression of at least one charge of gas, at least one motor piston rigidly connected to said first piston and slidably mounted in said motor casing delimiting a cylinder for said motor piston, a collecting chamber surrounding at least in part said cylinder and scavenging ports communicating said cylinder with said collecting chamber, said scavenging ports being successively closed and uncovered by said motor piston, a partition provided between said collecting chamber and said inlet scavenging air chamber, valve members mounted in said partition for communication from said inlet scavenging air chamber to said collecting chamber, said motor cylinder further delimiting an exhaust collector having openings for communication with said cylinder, said openings being successively closed and uncovered by said motor piston and a channel for location of a fuel injector.

2. A free piston machine comprising a motor casing and a compression casing rigidly connected in aligned relationship and externally provided with protruding cooling fins, a single movable unit located in said motor and compression casing to be reciprocated therein, said movable unit comprising a piston member mounted inside said compression casing, said piston member delimiting respectively on one and the other sides thereof an inlet scavenging air chamber and a compression chamber for the compression of at least one charge of gas, said single reciprocable unit further comprising a motor piston rigidly connected to said piston member and slidably mounted in said motor casing delimiting a cylinder therefor, said compression casing having outwardly extending ring projections and an annular sheath provided with a filtering member being connected to said ring projections and delimiting therewith an annular chamber into which project said cooling fins of said casing, inlet valve members carried by said compression casing and mounted on both

sides of said piston member respectively for communication between said annular chamber and said scavenging air chamber and said compression chamber for supplying thereof with air respectively during driving and driven stroke of said reciprocable unit, further said motor casing delimiting a collecting chamber at least in part surrounding said cylinder and communicating therewith by means of scavenging ports successively closed and uncovered by said piston during reciprocation thereof, cooling fins provided inside said collecting chamber and extending substantially in radial direction with respect to said cylinder for cooling thereof, a partition provided transversely between said collecting chamber and said inlet scavenging air chamber, valve members mounted in said partition for communication from said inlet scavenging air chamber to said collecting chamber, said motor cylinder further delimiting an exhaust collector having openings for communication with said cylinder, said openings being successively closed and uncovered by said motor piston, and a fuel injector leading to said cylinder for supplying thereof with fuel.

3. A free piston machine comprising a motor casing and a compression casing in aligned relationship, a single movable unit mounted to reciprocate inside said motor and compression casing, said movable unit comprising a piston member shaped substantially like a piston for compression in one direction of at least one charge of gas to be compressed and of at least one supplemental charge of air constituting a cushion charge intended to cause said unit to move in an opposite direction for compression of a charge of scavenging air, said unit further comprising two motor pistons integral with said piston member for driving thereof, said motor pistons being slidably mounted inside said motor casing delimiting two parallelly extending motor cylinders, a collecting chamber at least in part surrounding said cylinders, a transfer channel interconnecting said cylinders near the top part thereof, a fuel supplying recess also interconnecting said cylinders at the top part thereof, an exhaust collector partially surrounding one of said cylinders, scavenging ports between said collecting chamber and one of said cylinder, and exhaust openings between said exhaust collector and the other cylinder, a partition transversely extending between said motor casing and said compression casing, flat valves mounted inside said partition for the transfer of said scavenging air compressed by said piston member towards said collecting chamber of the motor casing, and inlet and outlet flat-valves carried by said compression casing on both sides of said piston member for inlet and outlet of said charges of gas to be compressed by said piston member.

4. A free piston machine as set forth in claim 3 in which said piston member comprises a flat piston rigidly connected on one of its sides to said motor pistons and a concentrically extending cushion piston of smaller diameter fixedely connected to the other side of said flat piston and into which further said compression casing delimits a compression cylinder for said flat piston, a cushion cylinder for said cushion piston and a discharge collector, discharge flat valves interposed between said compression cylinder and said discharge collector, inlet valve for said compression cylinder and a compressed air supplying mechanism for said cushion cylinder for the starting of the machine.

5. A free piston machine as set forth in claim 3 in which said piston member comprises a flat piston rigidly connected to said motor pistons, and said compression casing delimits a cylinder for said flat piston and is provided at its bottoms with inlet valve and at a distance apart from said bottom with discharge collector for the air compressed by said flat piston by which a closed compression chamber for the compressed air is provided between said bottom and said discharge valve for compression of the charge of air causing the return stroke of the unit.

6. A free piston machine as set forth in claim 3 in which said piston member comprises a flat piston rigidly connected to said motor pistons and said compression casing delimits a cylinder for said flat piston and is provided at its bottom with a discharge valve for communication with a discharge collector for the gas compressed by said flat piston, said flat piston and motor pistons connected therewith having longitudinally extending bores and said compression casing having cylindrically protruding fixedly mounted parts at least partially engaged into said bores and delimiting therewith closed chamber for the compression of the charge of air causing the return stroke of said movable unit.
